United States Patent Office

Des. 230,549
Patented Mar. 5, 1974

230,549

BED SHEET

Manuel C. Aires, 1253 136th Ave.,
San Leandro, Calif. 94578

Filed Dec. 27, 1971, Ser. No. 212,877

Term of patent 14 years

Int. Cl. D6—13

U.S. Cl. D6—264

The figure is a top plan view of a bed sheet showing my new design.

I claim:

The ornamental design for a bed sheet, substantially as shown.
